(57) **CLAIM**

The ornamental design for a saw blade, as shown and described.

DESCRIPTION

FIG. 1 is a perspective view of a saw blade;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is an enlarged detailed view of the saw blade as shown in rectangle 8 in FIG. 2.

The above drawings are lined to indicate color. In FIGS. 2 and 3, the colors change gradually from purple to gold toward the upper side. The overlapping portion of color bands is intended to indicate a gradual change in color between adjacent bands. In FIG. 7, the blade edges are colored in dark purple and the color changes reddish purple gradually toward the arch portion of blade bottoms.
